TYPEWRITING MACHINE

Charles Walker, Syracuse, N. Y., assignor to L. C. Smith & Corona Typewriters, Inc., Syracuse, N. Y., a corporation of New York

Application November 26, 1942, Serial No. 466,989

22 Claims. (Cl. 197—17)

The invention relates to improvements in typewriting machines, the general object of the invention being to provide an improved, more efficient, and more easily operated typewriting machine of the kind in which type impressions and concomitant letter space feeding of the paper which receives the type impressions are effected under control of manually operable type keys by power independent of that exerted by the typist in depressing the type keys.

The invention relates particularly to improvements in the means whereby type impressions and desired letter space feeding of the paper are effected.

The invention, more particularly, provides improved key-controlled power-actuated means for effecting selective actuation of the type carriers of the machine and concomitant letter space feeding of the paper which receives the type impressions; provides improved means for effecting key-controlled power actuation of a predetermined type carrier, or of either one of a plurality of predetermined type carriers of the machine, without effecting a letter spacing feed of the paper; provides an improved manually actuated space bar mechanism for effecting at will a letter spacing feed of the paper without effecting a type impression; provides improved key-controlled power-actuated means for effecting letter-spacing of the paper; and provides an improved and simplified and compact correlated construction and assembly of means for efficiently accomplishing the several aforesaid ends with great ease and a minimum of effort by a typist.

The invention also provides an improved construction and arrangement of parts (including the keys, the space bar, and adjacent portions of the main frame of the machine) affording an improved keyboard portion or section of the machine whereby the several keys and the space bar are operable by the typist with maximum ease, efficiency and comfort, and whereby the keyboard and adjacent parts of the main frame are so constructed and arranged as also to enhance the appearance and compactness of the machine.

Other purposes and advantages of the invention will appear from the following description in detail of the preferred embodiment of the invention illustrated in the accompanying drawings.

The invention, to the foregoing ends, comprises the arrangement of parts, features of constructions and combinations of elements and devices

particularly pointed out in each of the several appended claims.

The drawings illustrate the invention in accordance with a preferred construction, hereininafter particularly described, wherein the improvements are incorporated in a known L. C. Smith typewriting machine otherwise constructed substantially as is disclosed, for example, in United States patents to Gabrielson numbered 10 983,490, 1,018,968, 1,032,131, and 2,029,200, it being understood that said improvements may be embodied in other machines.

In the drawings;

15 Figure 1 is a fragmentary top plan view of the improved machine, certain parts being omitted and others broken away for clarity of illustration.

20 Figure 2 is a fragmentary vertical longitudinal sectional view taken substantially medially of the machine, certain parts being broken away and others omitted.

25 Figure 3 is a detail sectional view taken approximately on the line 3—3 of Figure 1 and showing features of the keyboard.

Figure 4 is a detail sectional view taken on the line 4—4 of Figure 3.

Figure 5 is a detail sectional view taken on the line 5—5 of Figure 3.

30 Figure 6 is a fragmentary front elevation of the keyboard portion of the machine.

Figure 7 is a detail sectional view taken on the line 7—7 of Figure 3.

Figure 8 is a detail sectional view taken approximately on the line 8—8 of Figure 9.

35 Figure 9 is a detail view, partly in section approximately on the line 9—9 of Figure 8, showing parts of the key-controlled power mechanism of the machine.

Figure 10 is a detail sectional view taken on the line 10—10 of Figure 9.

Figure 11 is a detail sectional view taken approximately on the line 11—11 of Figure 13, showing parts of the escapement and accent key mechanisms.

45 Figure 12 is a detail sectional view taken approximately on the line 12—12 of Figure 13.

Figure 13 is a fragmentary front elevation of a portion of the mechanism shown in Figure 11, certain parts being broken away.

50 Figure 14 is a detail sectional view taken approximately on the line 14—14 of Figure 1 and showing parts of the key-controlled power mechanism of the machine.

The illustrative embodiment of the invention shown in the drawings will now be described.

The machine illustrated has a suitable stationary main framework, portions of which are shown, said framework being generally designated by the reference numeral 10. The machine is provided with the usual roller platen 11 journaled in the usual platen carriage 12 which, in turn, is mounted on the framework as usual to travel transversely of the machine for letter feeding or spacing under control of the usual escapement device. This escapement device comprises the usual feed rack 13 fixed to the carriage, the usual feed pinion 2 meshing with said rack, the usual shaft 3 journaled in the main frame and to which is fixed said pinion 2 and the usual escapement ratchet wheel 4, the usual escapement dog rocker 5 pivoted at 6 on the main frame and carrying the usual pair of escapement dogs 7 and 8 coactive with wheel 4, the usual spring drum (not shown) mounted on frame 10, and the usual draw band (not shown) connecting the drum to the carriage to normally urge the carriage from right to left or in letter spacing direction.

The type bars 13 of the usual arcuate system of type bars (only one medial and one end one of which type bars are shown) have their pivots 14 carried by the usual type bar segment 15 which lies in an upwardly and rearwardly inclined plane, said pivots being arranged in an arc which lies in an upward and rearwardly inclined plane parallel to the aforesaid plane for striking of the effective types on the upper front portion of the platen as is usual in machines of the semi-front strike kind illustrated. Each type bar carries a lower case type 16 and an upper case type 17, the upwardly and rearwardly inclined type bar segment being shiftable by suitable case shift means (not shown) downward to an upper case typing position in which the segment occupies a lower position in its inclined plane to condition the machine for upper case typing. The means for supporting and shifting the type bar segment may be those disclosed in the previously mentioned Gabrielson Patent 2,028,200, or any other suitable means. Adjacent their forward ends, the type bars are normally supported by the usual upwardly and rearwardly inclined arcuate type bar rest 18 which is supported as usual by means not shown to shift with the type bar segment 15.

Each type bar has pivoted thereto at 19, at a point normally above and forward of its pivot 14, the forward end of a different one of the links of a series of rigid draw links 20, the rear ends of which are connected by pivots 21 to the upper ends of the respective ones of a series of sub-levers 22, the links 20 being all of the same length. The pivots 19 and the pivots 21, respectively, lie in obliquely disposed parallel arcs which are concentric with and are disposed in planes parallel to those of the type bar segment and the series of type bar pivots 14 so that, when the segment is case shifted, the links 20 will hinge about pivots 21 as is common in segment shift machines.

The several sub-levers 22 (only a medial and an end one of which are shown) are pivoted in slots in a vertically disposed segment 94 fixedly held to frame work 10, and said sub-levers have their pivotal axes 23 located in an arc which is of greater radius than that of the series of pivots 21 and is disposed in a vertical plane transversely of the machine. The lower arms of the levers 22 are shaped so that their lower portions are normally registered or arranged in a straight row

extending transversely of the machine, and each such lever is formed forward of its lower arm with a finger 22a permanently bendable or adjustable fore and aft of the machine, the levers being formed of sheet metal adapted for formation of permanent bends therein. These fingers are engageable with the upper portions of standing cushioning and type bar repulsing leaf springs 24 before the type bars reach printing position on their printing strokes, said springs being arranged in a straight row extending transversely of the machine forward of the fingers 22a and being secured at their lower ends to a part of the stationary framework 10 of the machine. The construction is such that each lever 22 has two arms of substantially equal effective length.

The lower arm of each sub-lever 22 has pivotally connected thereto at the lower end thereof at 25 the forward end of a different one of a series of rearwardly extending couplers or interponents 26, the couplers being normally arranged in a straight horizontal row across the machine with the pivots 25 in axial register for selective swinging of the couplers up and down about a straight horizontal axial line extending transversely of the machine. Above and to the rear of their pivots, the couplers have connected thereto the forward ends of a row of type bar and coupler return springs 27 anchored at their rear ends to a part of the stationary framework 10. These springs normally yieldingly hold the type bars against type bar rest 18 and hold the couplers against a horizontal and straight coupler rest 28 which extends transversely of the machine. The couplers normally extend to the rear of rest 28 through vertical guide slots in a coupler guide comb 29 which extends horizontally across the machine, said coupler rest and guide comb being mounted on a part of the stationary framework 10 and being preferably adjustable fore and aft of the machine. The rear edge of the coupler rest is undercut as shown at 28a, and each coupler is formed with a forwardly facing and forwardly and downwardly inclined shoulder 30 (Figure 8) normally spaced slightly rearward of the undercut rear edge of the coupler rest to permit upward swinging of the coupler about its pivot 25 but engageable with said undercut edge by a very slight rebound of the type bar from its rest 18 to lock the connected type bar against any appreciable rebound from the type bar rest. Each coupler 26 is formed with a rearwardly facing shoulder 31 which is slightly undercut at its upper end and is normally located rearward of comb 29 and, at the lower edge of each coupler, the coupler is formed with a rearwardly extending finger 32, the upper edge of which extends rearward from the lower end of shoulder 31.

A universal type bar actuator 33, comprising a straight bar extending horizontally across the machine and formed at its ends with pendent side arms, has the lower ends of its side arms fixed to a horizontal rock shaft 34 which, in turn, extends horizontally across the machine and is journaled at its ends at 35 on the main framework 10. The cross bar of the actuator normally overlies and is spaced above all of the coupler fingers 32, and the straight forward edge of this actuator cross bar is normally located above and slightly to the rear of the upper ends of coupler shoulders 31.

The actuator 33 constitutes a tappet device which is rockable forwardly a predetermined distance from a normal idle position by means of

two constantly tensioned pull springs 36 connected at their rear ends to the side arms of the actuator and at their forward ends to the framework 10, to impel a selected type bar by spring power toward printing position for final type impressing travel of the type bar solely under the influence of acquired momentum as herein-after explained.

The actuator 33 is retracted to normal position by power superior to that of springs 36 and derived from a constantly rotating shaft 49 which is constantly driven counter-clockwise (as the machine is viewed in Figures 2, 8 and 10) by means of an electric motor 9 while the machine is in use. Said motor is fixedly mounted on the framework 10 within the framework and is connected to shaft 49 by suitable speed reduction driving means 9a also located within the framework 10. Shaft 49 extends horizontally transversely of the machine in rear of the actuator 33, is journaled in the framework 10, and has fixed on its right hand end a ratchet wheel 50.

Opposite the ratchet wheel 50, and adjacent thereto at the right thereof, there is journaled in the framework 10 a short crank shaft 51, the axis of which is coaxial with that of shaft 49. A pitman 52 has its rear end pivotally and detachably connected to the wrist of crank shaft 51 and has its forward end pivotally and detachably connected to a bracket 53 fixed on the cross bar of the actuator 33. The front end of the pitman is connected to bracket 53 by a shoudered pivot screw 54. At its rear end the pitman is formed with a hook 55 (Figure 2) engaged over the wrist of crank shaft 51. A retaining plate 56 (Figures 2 and 9) has a forked rear end which receives the wrist of the crank shaft and closes the throat of the hook, the front end of said plate being detachably held to the rear section of the pitman 52 by a clamping screw 57. The pitman comprises two sections having adjacent threaded end portions adjustably connected by a turnbuckle 58 for lengthening and shortening of the pitman to vary the normal or retracted position of the actuator 33. Turnbuckle 58 is locked, with the pitman in adjusted condition, by lock nuts 92.

Crank shaft 51 is adapted to be clutched or connected with shaft 49, for a part of a single revolution, through the medium of the ratchet wheel 50 and a pawl 59. Pawl 59 is pivoted substantially midway its ends on a horizontal pivot screw 60 extending transversely of the machine and threaded into an arm or pawl carrier 61 which, in turn, is fixed on the left hand end of the crank shaft 51 to rotate opposite the right hand face of the ratchet wheel 50. One arm of the pawl has a nose engageable with the teeth of the ratchet wheel, and a torsion spring 62 is coiled about a spacing sleeve 62a on the shank of pivot screw 60 and has its opposite ends engaged with said arm of the pawl and with the pawl carrier to normally constantly tend to urge the pawl nose into engagement with the teeth of the ratchet wheel.

Means are provided for manually selecting any desired type bar for actuation and for causing actuation of the selected type bar by the above described power operated mechanism, which means will now be described.

A part of the framework 10 is formed with an arcuate pawl controlling surface 63 which curves downwardly behind and under the periphery of

the ratchet wheel 50 concentrically with the coincident axes of the shafts 49 and 51 and extends about said axes for somewhat less than 180 degrees. This surface is so disposed that the arm of the pawl 59 opposite the nose carrying arm of the pawl is normally engaged with said surface adjacent the upper end of said surface as indicated more clearly in Figures 8 and 10 to hold the nose of the pawl out of engagement with the ratchet. At this point in the revolution of the crank shaft, the wrist thereof is to the rear of the shaft axis and slightly below dead center or a straight line through the centers of said shaft and the screw 54, and the outer end of the pawl carrying arm 61 is seated upon and held arrested by a spring-cushioned latching or stop lever 64 (Figures 8 and 9). On a working stroke of the actuator 33 the pawl passes out of engagement with surface 63 at the lower end of said surface and is swung by its spring into engagement with the ratchet wheel 50 just before the crank shaft wrist reaches a dead center position in front of the shaft axis.

The stop lever 64 has two stop lugs 64a and 64b for limiting its rocking movement about a horizontal pivot 64c carried by a fore and aft rockable arm 65 pivoted at its lower end at 66 on the framework 10. Said latch or stop lever 64 is normally held with the forward end thereof at the upper limit of its motion by means of a stiff spring 67 (Figure 8) which is connected to the rear end of the lever 64 and to arm 65 and is adapted to yield momentarily under impact of arm 61 on the forward end of the latch or stop lever 64. A universal release bar 68 extends straightly and horizontally transversely of the machine and is normally located intermediate the cross bar of actuator 33 and the fingers 32 formed on the type action couplers 26. This release bar 68 is provided with rearwardly extending arms fixed thereto adjacent opposite ends thereof and fixed to a rock shaft 69 which extends horizontally transversely of the machine at the rear of said bar and is journaled at its ends on framework 10 at 69a. A link 70 (Figures 8 and 9), pivotally connected at its rear end at 71 to arm 65 near the upper end of the latter, is adjustably and pivotally connected at its forward end with an upstanding rock arm 72 fixed to rock shaft 69. This latter connection comprises the normally upstanding arm or part 72 fixed to and extending above rock shaft 69, an upstanding arm 73 having a forked lower end pivoted on shaft 69 for adjusting movement fore and aft of the machine, a clamping screw 75 which extends through a slot 73a in the adjustable arm 73 above shaft 69 and is threaded into the upper portion of arm 72 to clamp arm 73 to arm 72 in adjusted position, and a pivot screw 95 connecting link 70 to arm 73. A return spring 77, connected to one of the release bar supporting arms and to the framework 10, normally returns the release bar 68 and arm 65 to position the stop 64 in pawl carrier arresting position, said spring normally urging the upper end of arm 72 forward against a cushion stop 79 held to framework 10.

Upon upward swinging of any one of the couplers 26 about its pivot 25 into a position placing coupler shoulder 31 in front of the cross bar of actuator 33 for forward driving of the upwardly swung coupler by the actuator, the finger 32 of the upwardly swung coupler will rock release bar 68 upward and rearward to disengage stop or latch 64 from the pawl carrier 61 and release

the actuator 33 for forward movement by its impelling springs 36.

The pulling force exertible by the pull springs 36 on the actuator 33 to cause the latter to impel a selected type bar to the printing point is preferably only sufficient for proper printing upon a single sheet, and the following means are provided for variably increasing at will the type bar impelling force exerted by the actuator to obtain heavier type impressions for manifolding and other purposes. An upstanding rock arm 38 is fixed to the actuator rock shaft 34 near the fore and aft medial line of the machine or substantially midway between the ends of the actuator. A horizontal rock shaft 40, which is journaled at its ends on the framework 10 at 41 in advance of shaft 34, extends inward from the right hand side of the framework transversely of the machine to a point near the fore and aft medial line of the machine and has fixed thereon near its inner end a pendent rock arm 42 and near its outer end a forwardly extending rock arm 43 (Figures 1 and 14). Arms 38 and 42 are connected by a rigid fore and aft extending link 39. A bellcrank lever 44, which is pivoted on the framework 10 at 45 to rock about a horizontal axis extending transversely of the machine substantially above the axis of shaft 40, has a forwardly extending arm connected with arm 43 by a pull spring 46 and has an upstanding arm connected by a rigid link 47 with the outwardly extending arm of a bellcrank 48. Bellcrank 48 is pivoted on the framework 10 for swinging adjustments about a vertical axis 80. The bellcrank 48 has a forwardly extending handle arm which is slightly resiliently flexible up and down and provided with a latching stud or pin 81 releasably engageable in either one of an arcuate series of holes 82 formed in a horizontal latch plate 83 fixed to the framework 10. Holes 82 are arranged in an arc struck from axis 80.

Spring 46, when the handle arm of bellcrank 48 is latched in the hole at the inner end of the series of holes 82, in the position shown in Figure 1, preferably has no tension or only enough tension to prevent accidental disconnection of the spring from its anchorages and, therefore, exerts no appreciable force on the actuator in this adjusted position of the bellcrank. By swinging the handle arm of bellcrank 48 outwardly and latching it in one or the other of the remaining holes 82, the spring 46 may have imposed thereon a normal tension which will vary with the hole in which the pin 81 is engaged. The spring tension thus imposed on spring 46 will be imposed on the actuator 33 in addition to that imposed by springs 36 to thereby increase the type bar impelling force exertible by the actuator.

The release bar 68 is operable from any one of the type keys 100 of the keyboard of the machine to release the actuator 33 for a single advancing and retracting actuation of the actuator.

The type keys 100 are arranged in four rows across the machine and are fixed on the upwardly and forwardly extending front ends of short and parallel fore and aft extending type key levers 101 which have also upstanding rear ends. The upstanding rear ends of the key levers 101 are fulcrumed in slots 102 in a straight horizontal bar 103 fixed to the framework 10 and extending transversely of the machine close to the rear end of the keyboard and below the forward end of the system of type bars, the key levers being fulcrumed on a straight horizontal pivot

wire 104 carried by bar 103 and extending through all of the slots 102.

Below the segment 94 and the lower ends of sub-levers 22, a straight horizontal bar 105 fixed to framework 10 extends transversely of the machine, is provided with a series of vertical slots 106 across its front edge, and carries a straight horizontal fulcrum wire 107 which crosses all of said slots 106. Engaged in slots 106 and fulcrumed on wire 107 are identical sub-levers 108 (one for each key lever), said sub-levers lying in parallel vertical planes disposed fore and aft of the machine. Each sub-lever 108 has an arm which extends downwardly from its fulcrum and is formed with a rearwardly projecting portion extending under bar 105 and coupler rest 28 and also extending through the actuator bail 33 below the universal release bar 68.

The downwardly extending arm of each sub-lever 108 is connected by a rigid link 110 with a pendent lug 111 formed on the upstanding rear portion of the associated one of the key levers 101 adjacent the lower end of said key lever portion. Links 110 are all of the same length, and lugs 111 are permanently adjustably bendable fore and aft of the machine. The front ends of the links are pivoted to lugs 111 at 111a. The links 110 for key levers supporting different banks of keys are connected to the pendent parts 30 of the lower arms of the sub-levers 108 at different elevations at 109a, 109b, 109c and 109d for the first or rear, second, third, and fourth or front banks of keys, respectively, for uniform key dip and uniform rocking of the sub-levers.

To the rearwardly extending portion of the lower arm of each sub-lever 108 is anchored the rear end of one of a row of return springs 112, the forward ends of which are anchored to framework 10, to restore the sub-levers, links 110 and key levers 101 to normal position. Each sub-lever 108 has an upper and short upstanding stop arm 113 normally abutting the rear end wall of the slot 106 in which said sub-lever is pivoted. The fore and aft extending portion of each type key lever 101 is formed with a pendent stop lug 114, which is permanently adjustably bendable fore and aft of the machine and normally abuts the rear face of a cushion stop device 115 to limit return movement of the key lever. The stop device 115 extends straightly and horizontally across the machine below the forward portions of the key levers and is clamped in fore and aft adjusted position to the framework 10 by suitable screws as 116 which extend through fore and aft 55 extending slots in the stop device and are threaded into the framework, as shown in Figure 3. A vertically slotted key lever guide comb 117 is fixed to framework 10 immediately forward of the stop device 115 for up and down movement of the fore and aft extending portions of the type key levers in the slots of said comb, the key levers for the rear row of keys having their fore and aft extending portions extended forward of their upturned key carrying portions 60 for engagement in the comb, as shown in Figure 3.

The rearwardly extending portion of the lower arm of each sub-lever 108 has pivoted thereon at 118 a normally upstanding and fore-and-aft rockable two-armed, coupler-lifting thrust lever 119, the lower arm of which thrust lever is connected by one of a row of return springs 120 to the rear end of said sub-lever arm portion to normally hold the upper arm of the thrust lever 119 urged forward against a straight horizontal cushion

stop 121. Pad 121 is fixed to a thrust lever guide comb 122 which is held to framework 10 and extends horizontally and straightly across the machine. Each thrust lever 119 has a laterally bent upper end portion engageable with but a single associated one of the couplers 26, its upper end being normally spaced slightly beneath the finger 32 of the associated coupler. The rearwardly extending portion of the lower arm of each sub-lever 108 is also formed with a rearwardly extending stop lug 123 which is permanently bendable up and down and is adapted to rise into contact with a straight horizontal cushion stop pad 124 to limit the movement of the sub-lever by depression of the type key on the associated key lever and also limit the extent of depression of said key, the said stop pad 124 extending transversely of the machine and being fixed to the under face of comb 122.

Upon depression and release of any one of the type keys, its associated type bar is actuated to effect a single type impression and to return to and remain in normal position whether or not the key is promptly released. Depression of the selected type key lifts the associated thrust lever 119, which thereupon rocks the associated coupler 26 upwardly about its pivot 25 to place coupler shoulder 31 immediately in front of the cross-bar of actuator or tappet device 33 and simultaneously cause finger 32 of said coupler to rock the release bar 68 upwardly to shift latch 64 rearwardly out of engagement with pawl carrier 61 to release the actuator 33. Springs 36 thereupon instantly pull the actuator forward at high speed to the limit of the forward stroke of the actuator thereby driving the coupler forward with a spring impelled tappet action of the actuator on the lifted coupler. At the limit of the forward stroke of the actuator, the sub-lever finger 22^a contacts the associated cushioning and repulsing spring 24 while the type on the type bar is still spaced appreciably from the paper backed by the platen, after which the type bar completes its printing stroke by reason of acquired momentum against the resistance of said spring 24 and is then quickly repulsed from the platen by said spring. The final portion of the printing stroke of the type bar carries the coupler forward out of contact with the universal type bar actuator or tappet 33 and thrust lever 119, and the coupler thereupon instantly drops down upon the coupler rest 28, thus freeing both the release bar 68 and the latch device 64-65 for instant movement back to normal position by spring 77 for arresting the pawl carrier 61 by the latch device 64-65 at the end of a single revolution of the pawl carrier. On the return stroke of the type bar by springs 24 and 27, the coupler slides under the release bar, and, if the type key is still held depressed, the coupler finger 32 will abut the upper arm of lifting lever 119 and rock the same rearward below the returned release bar and, when the key is finally released, the lever 119 will be restored to its normal position by the associated spring 120. If the key is released instantly after full depression thereof, the coupler finger 32 will move rearward between the returned release bar 68 and the returned lifting lever 119 into the normal position of the finger and coupler. Just before the actuator is fully advanced by its impelling springs 36 (or 36 and 46), the pawl 59 passes out of contact with surface 63 at the lower forward end of said surface and its nose snaps into engagement

with the constantly rotating ratchet 50 which thereupon drives crank shaft 51 positively through the remaining somewhat more than one-half of its single revolution whereupon the pawl is kicked out of engagement with the ratchet by coming into contact with the upper end of surface 63. As the pawl is disengaged from the ratchet, its carrier arm 61 impacts the restored yieldable stop 64 and is finally brought to rest by said stop at the starting point or normal position of the carrier arm. The actuator is thus positively retracted to normal idle position against the resistance of springs 36 (or 36 and 46), and the selected type bar will make but one impression irrespective of the length of time its controlling type key is held depressed.

Means are provided whereby the escapement of the machine is normally operable by the type bar actuator for effecting a letter space feed of the platen carriage concomitantly with each type impression, but whereby any selected one, or plurality of selected ones, of the type actions may function as accent, silent or dead type actions, i. e., type actions operable to print without causing a letter feed movement of the carriage. Means are also provided whereby the escapement may be manually operated by the space bar of the machine.

The dog rocker 5 carries the usual adjustable return stop 125 engageable with a part of framework 10 to determine the normal position of the dog rocker, said rocker being yieldingly held in normal position by the usual dog rocker return spring 126. At its front side the dog rocker is formed with two closed spaced parallel and vertically disposed webs 127 projecting forwardly from the rocker, between which webs the upstanding arm of an angle lever 128 is closely confined and rockably adjustable. This lever arm is pivoted substantially midway its ends on a horizontal pin 129 which extends between said webs parallel to and forward of the dog rocker pivot 6 and is held to said webs. Two fore and aft extending adjusting screws 130 are threaded through the dog rocker, one above and the other below the rocker pivot and bear against the rear edge of the upstanding arm of lever 128 respectively above and below pivot pin 129 to hold the lever against rocking on its pivot pin with the lever in selected adjusted relation to the dog rocker. Suitable lock nuts 130^a are threaded on screws 130. Lever 128 has a forwardly extending arm projecting from the lower end of its upstanding arm. A rigid escapement-tripping pull link 131 is connected at its upper end to the forward end of said forwardly extending arm of lever 128 by a horizontal pivot 132 for swinging of said link fore and aft of the machine by means hereinafter described.

Below the lever 128, and substantially directly below the pivot 129 thereof and in rear of the release bar rock shaft 69, is a short horizontal rock shaft 133 which extends transversely of the machine and is medially located between the sides of the machine, said rock shaft 133 being journaled at its ends on the framework 10 at 134. Fixed to shaft 133 substantially midway between the ends of said shaft is a narrow forwardly extending yoke which comprises a pair of parallel forwardly extending and closely transversely spaced side arms 135 (fixed to said shaft) and also a short horizontal cross pin 136 fixed at its ends to the forward ends of said side arms. The link 131 extends downward through this

yoke 135—136, maximum fore and aft movements of the link being limited by shaft 133 and pin 136 and sidewise movements of the link being limited by arms 135. The forward edge of link 131 is recessed adjacent the lower end of the link to provide a hook 137 which is normally engaged with and under cross pin 136 of the yoke 135—136. The shaft 133, arms 138 and 157 (hereinafter described) and yoke 135—136 form an escapement tripping tappet device normally coacted with the hook device 131—137.

Shaft 133 has fixed thereto to the left of the yoke 135—136 a pendent rock arm 138 which carries at its lower end a laterally extending pin or stud 139 movable back and forth in a short fore and aft extending arcuate slot 140 in a pendent arm 141 loosely pivoted at its upper end on shaft 133. Substantially directly above shaft 133 and forward of the constantly running power shaft 49, there is fixed to framework 10 a short rod 142 which extends horizontally transversely of the machine and is located substantially medially of the sides of the machine. A torsion spring 143 wrapped around this rod has its opposite ends abutting shaft 133 and a pin 144 on link 131 to normally hold the link pressed forward against pin 136 of yoke 135—136 with the hook 137 on said link engaged with and under said pin 136. A torsion spring 145 wrapped around shaft 133 has its opposite ends engaged with rod 142 and with pin 139 on rock arm 138 to normally hold said pin 139 engaged with the forward end of slot 140 in the pivoted arm 141. The lower end of the freely pivoted arm 141 is connected by a rigid forwardly and downwardly extending link 146 to the rear end of a normally forwardly and downwardly extending rock arm 147 fixed on the rock shaft 34, to which shaft 34 the type bar actuator 33 is also fixed as previously described, thus providing a toggle for actuating the escapement tripping tappet device.

An escapement disabling rock shaft 148 extends horizontally transversely of the machine across the entire system of type actions, said shaft being journaled at its ends at 149 on framework 10 and passing between yoke 135—136 and the link 146 forward of arm 141 and in rear of the sub-levers 108. For each type key 100 of the keyboard selected to function as a silent or accent key, there is detachably clamped to shaft 148 a J-shaped tappet 150 which extends forwardly from said shaft, two such tappets for two different keys being shown in Figure 1. It will be understood that as many of these tappets as desired may be employed. Each such tappet is clamped to shaft 148 by a clamping screw 151 engaged with the legs thereof with shaft 148 between said screws and the bend connecting the legs of the J-shaped tappet. The longer leg of each tappet extends forwardly to immediately overhang the rear portion of the desired sub-lever 108, each such tappet overhanging only a single sub-lever. Each tappet employed is adjustably clamped to the shaft by its screw 151 for axial and radial adjustment respectively along and about said shaft. Fixed on shaft 148 is a rigid upstanding tappet arm 152 provided at its upper end with a laterally extending lug 153 normally disposed immediately in front of the lower end of the escapement trip link 131 below hook 137 of said link and disposed out of the paths of normal escapement tripping movements of the link 131 and yoke 135—136. A return torsion spring 154 (Figure 13), wrapped around shaft 148 and having its ends engaged with said shaft and with

framework 10, normally urges said shaft clockwise as viewed in Figures 2 and 11 to urge a stop 155, held to said shaft, against a stop 156 fixed on framework 10, to thereby normally yieldingly hold tappets 150—151 and 152—153 positioned as shown. Stop 155 is constructed similarly to tappets 150—151 for clamping of the stop to shaft 148 in different adjusted positions about said shaft. The shaft 148, and the several arms or tappets 151 and 152 fixed thereto, form a spring-returned escapement disabling tappet device.

The spring-returned escapement tripping tappet device, comprising the shaft 133, arms 138 and 157, and yoke 135—136, is also manually rockable by a space bar 163 in the keyboard portion of the machine to trip the escapement for letter spacing.

Fixed to shaft 133 to the right of yoke 135—136 is a short pendent rock arm 157 carrying at its lower end a laterally extending pin 158 movable in a short fore-and-aft extending arcuate slot 159 in a longer pendent arm 160 which is loosely pivoted at its upper end on shaft 133. The return spring 145 for the escapement tripping tappet device 133—135—136—138—157 also normally yieldingly maintains pin 158 at the forward end of slot 159.

To the lower end of arm 160 there is pivoted at 161 the rear end of a long fore-and-aft extending space-bar-actuated link 162 located substantially midway between the sides of the machine. The space bar 163 is located forward of the rows of type keys 100 of the keyboard and will be hereinafter more particularly described in connection with other details of the keyboard portion of the machine. Below and forward of the front row of type keys of the keyboard there is journaled in the framework 10 a horizontal rock shaft 165 which extends transversely of the machine. Fixed to this shaft adjacent its opposite ends are two forwardly extending rock arms 166 connected at their forward ends, by horizontal pivots 167 which extend transversely of the machine, to two rearwardly extending brackets 168 fixed to the space bar and located under the top of said space bar. Two fore-and-aft extending links 169, parallel to and at a higher level than arms 168, are pivoted at their forward ends at 170 to brackets 168 and at their rear ends at 171 to framework 10 above the shaft 165 for up and down rocking of said links in parallelism with said arms. Substantially midway its ends and substantially medially of the sides of the machine, the rock shaft 165 has fixed thereto a pendent rock arm 172, the lower end of which arm is connected by a horizontal transversely extending pivot 173 to the forward end of the space bar actuated link 162 above described. A pair of space bar return springs 174, anchored to the space bar and to framework 10, yieldingly hold the space bar and its connected escapement operating train 169—166—172—162—160 normally positioned as shown, while arm 141 and its connecting train 146—147 to the actuator 33 are normally positively held positioned as shown by the normally retracted and latched actuator 33, and the escapement tripping tappet device 138—157—133—135—136 is normally yieldingly held as shown by spring 145. The space bar return springs 174 normally yieldingly hold one head of a double-headed cushion stop 175, fixed on rock arm 172, pulled forward against a pendent stop finger 176 formed on a part of framework 10 which finger is permanently bendable fore-and-aft of the machine, and depression of the space

bar is limited by engagement of the other head of said stop 175 with a rearwardly extending stop finger 177 formed on a part of framework 10, which finger 177 is permanently bendable up and down.

The slots 159 and 140 and associated pins 158 and 139 form lost motion connections to permit the escapement tripping tappet device 157—138—133—135—136 to be rocked by actuator 33 without resultant movement of the space bar and its connection to said device, and to permit rocking of said device by the space bar 163 without resultant movement of the actuator and its connection to said device. The lost-motion in these two connections is normally taken up by the action of spring 145 on pin 139. Rocking of the escapement disabling device (comprising parts 152, 153, 155, 148 and one or more of the tappets 150—151) by depression of a silent, dead or accent type key swings escapement trip link 131 rearward to disconnect its hook 137 from pin 136 of the escapement tripping tappet device on the down stroke of the key prior to release of the actuator 33 and prevents actuation of the escapement dog rocker 5 by the ensuing type-impressing operation of the actuator 33.

When any type key is depressed and released, the actuator 33 will move forward and then be retracted and latched, as above described, to cause the associated type bar to print and permit return of the type bar. If the key is one of the ordinary or "live" keys, the reciprocation of the actuator will trip the escapement to feed the platen carriage one letter space, but, if the actuated type key is a "dead" or accent key, the rear end of its associated sub-lever 188 will, when lifted by manual depression of the key, rock the associated dead key tappet 150—151 to thereby rock the shaft 143 and the escapement disabling tappet 152—153 on said shaft to swing link 131 rearward and manually disconnect the hook 137 on said link from pin 136 of the escapement tripping tappet device 138—151—133—135—136 on the down stroke of the key, so that the ensuing automatic power operation of said escapement tripping tappet device by the actuator 33 will not trip the escapement.

Depression and release of the space bar 163 manually rocks the escapement tripping tappet device 138—151—133—135—136 to manually trip the escapement to feed the carriage one letter space. Whenever a type impression is made, the actuated type bar is spring-impelled to print and is spring-returned and, whenever the escapement dog rocker is power actuated concomitantly with a type bar, said dog rocker is likewise spring-impelled and spring-returned.

The main framework of the machine includes a base casting having side walls 10^a, a rear wall 10^b and a front wall 10^c. To this casting there is secured, by screws 178, a flat keyboard guard plate 179 which inclines downwardly and forwardly to the top inner edge of front wall 10^c of the casting. All of the keys of the keyboard (including the type keys 100 and the usual special keys) are disposed in an inclined plane parallel to that of plate 179, and the plate is provided with circular apertures 180 (one for each such key). The keys normally protrude through these apertures with their lower portions loosely engaged in the apertures, and the dip of the keys is such that their tops are substantially flush with the top face of the plate at the lower limit of key depression, the tops of the keys being inclined parallel to said plate. The dip of the keys and

space bar are all equal and of very slight extent, namely about one-eighth of an inch, one purpose of the construction shown being to provide for such slight uniform key and space bar dip.

5 The front wall 10^c of the base casting is recessed along its top and front at 181 and 182, respectively, between the ends of said wall to accommodate the space bar and its supporting means and return springs, and permit the slight operative depression of the space bar, with the space bar located within the confines of the front and side walls 10^c—10^a. The space bar is formed of sheet metal or rigid sheet material and has a flat, forwardly and downwardly inclined top portion 163^a, disposed in a plane parallel to the planes of plate 179 and the keys 100 and normally located in a plane intermediate those of the plate and the key tops, for engagement by a thumb of the typist to depress the space bar. The rear edge of part 163^a of the space bar is provided with a pendent stiffening flange 163^b opposed to the front edge of plate 179. Pendent from the front edge of part 163^a of the space bar is a skirt portion 163^c extending downward substantially to the bottom of the base casting in front of recess 182 in the front wall of the casting and in front of springs 174 which are anchored at their lower ends to pins 174^a on this skirt. The skirt is flush with the front face of the end portions of the front wall 10^c of the base casting. A compact keyboard and space bar assembly in which the keys and space bar may be easily and comfortably manipulated is thus provided.

35 The concept of combining a series of spring-returned type bars and a spring-returned escapement dog carrier with a normally idle key-controlled and power-actuated tappet mechanism which is spring-impelled to concomitantly activate the dog carrier and a key-selected type bar in opposition to the return spring force constantly exerted on said dog carrier and type bar, affords a highly efficient working action of the parts and also provides a construction wherein the inertia shocks resultant from return arrest of the tappet mechanism at the end of each cycle of operation can not be transmitted to either the escapement or the type bars, wherein the inertia shocks resultant from return arrest of the dog rocker and an activated type bar and from reversal of direction of motion of the rocker and activated type bar are not transmitted to the power actuated tappet mechanism, and wherein the positive power retraction of the tappet mechanism to stress the tappet mechanism impelling springs cannot positively jam an escapement dog against the escapement wheel upon sluggish letter feed movement of the carriage and thereby either damage the escapement dog or wheel and/or power mechanism or jam the machine against operation with the parts out of normal position.

60 65 70 75 The further concept of embodying in said tappet mechanism a universal type bar impelling tappet, and also a spring-returned dog-rocker-impelling tappet operable in opposition to its return spring from the type bar impelling tappet by a purely thrust connection or tappet like action, and of combining with said two tappets a manually operated and spring-returned space bar having a solely one-way thrust connection with the dog rocker impelling tappet for rocking the latter in opposition to its return spring, provides simple and effective means whereby the escapement may be tripped by the power-actuated type bar impelling tappet without moving the space bar and may be tripped by the space bar without

causing a power actuation of the type bar impelling tappet.

The further concept of providing an escapement tripping interponent yieldingly normally interposed for actuation by the dog rocker impelling tappet of the power actuated tappet mechanism, and of associating with said interponent a spring-returned escapement disabling tappet manually operable by any predetermined one or ones of the keys during depressing of the latter to shift the interponent temporarily out of the path of the dog rocker impelling tappet, affords a simple and compact and efficient arrangement whereby any predetermined one or ones of the keys may function as silent or accent keys for effecting printing without letter spacing.

The construction and arrangement of the parts constituting the keyboard portion of the machine permits actuation of the keys and space bar with maximum ease and comfort and a minimum of exertion, and also provides a compact keyboard portion which has a pleasing appearance and also reduces the length of the machine.

It will be observed also that the construction and arrangement of the power actuated tappet mechanism, and of the key operated mechanism for controlling said power actuated mechanism, are such that these mechanisms are very compactly distributed within a base casting of a very low maximum height not substantially exceeding the maximum height of the keyboard, thus leaving ample room for the remaining portions of the machine.

It will also be observed that the improved construction which the present invention provides is characterized as a whole by the fact that it consists of a correlated assembly of devices and mechanisms wherein each mechanism or device operative on another acts thereon solely with a tappet action or thrust action in one direction only, and the concept of such an assembly of mechanisms or devices makes possible precise relative adjustments between the several interrelated mechanisms or devices for correct and efficient action and also makes possible separate assembly of the several devices or mechanisms for more facile and correct assembly of the parts of the machine.

The key-operated trains are adjustable relatively to the couplers 26 and the type bars connected therewith, and are operative on the couplers with a tappet action; the release bar 68 and the actuator 33 are separately adjustable relatively to the couplers which act on the release bar with a tappet action; the escapement tripping tappet accommodates itself to adjustments of actuator 33 and the space bar, both of which are effective on said tappet solely with a tappet or thrust action in one direction only; the escapement tripping tappet acts on link 131 with a tappet action and this link is adjustable relatively to the tappet by reason of its adjustable anchorage to the escapement dog rocker; and the dead or accent key tappet device is actuated by a tappet action thereon of predetermined ones of the sub-levers 108 and is operable upon link 131 with respect to which, and to the key operated mechanisms which act on said dead key tappet device, the latter is adjustable by reason of the adjustable clamping anchorages of elements 150 and stop 155 to shaft 148.

The provision of the aforesaid correlated assembly of interactive tappet devices or mechanisms constitutes one important feature of the inventive conception exemplified by the construc-

tion illustrated in the drawings and described above.

I claim:

1. In a typewriting machine, the combination of a platen carriage, a platen on the carriage, a letter feed escapement means for the carriage including an escapement dog carrier, type carriers coactive with the platen, a vibrative universal actuator, spring means for impelling said actuator in one direction, superior power means for retracting the actuator against the power of said spring means, interponents connected with the respective type carriers and normally out of the field of movement of the universal actuator, type keys, an interponent setting train for each type key and interponent and each operable by depression of its associated key to engage and set its associated interponent for actuation by the universal actuator on the spring-impelled stroke of the latter to propel the associated type carrier toward the platen, means operable by setting movement of any one of said interponents to release the universal actuator for a single vibration of said universal actuator by its impelling spring means and the superior power means and to thereupon lock the actuator in retracted position, a separable actuating train between the universal actuator and the escapement dog carrier the separable portions of which are connected respectively to the dog carrier and the universal actuator, a return spring for the dog carrier and the portion of said dog carrier actuating train connected with the carrier, a return spring for each key and its associated interponent setting train, a return spring for each type carrier and its associated interponent, and a spring-returned escapement disabling device operable by interponent setting movement of one or more of the interponent setting trains to separate the dog carrier actuating train to prevent actuation of the dog carrier by the universal actuator.

2. In a power actuated typewriting machine, the combination of a platen carriage, a platen thereon, spring-returned printing instrumentalities, a carriage escapement including a spring-returned escapement dog rocker, individual type key controlled mechanisms for selectively conditioning the respective printing instrumentalities for printing actuation, a single actuating mechanism for concomitantly actuating both the dog rocker and any selected printing instrumentality in opposition to the return spring power exerted on said rocker and instrumentality, a motor constantly driven while the machine is in use, spring means for impelling said actuating mechanism to actuate the dog rocker and selected printing instrumentality in opposition to the return spring power exerted on the rocker and selected printing instrumentality, and means controllable by each of said key-controlled mechanisms to release said actuating mechanism for spring impulsion thereof and to thereafter first connect said mechanism to said motor for motor actuation of said mechanism in opposition to the power of its impelling spring means and then disconnect said motor from said mechanism and hold the latter against operation by its impelling spring means, said single actuating mechanism for concomitantly actuating the dog rocker and selected printing instrumentality being operable thereon to move the same in one direction only.

3. A typewriting machine, as claimed in claim 2, having means operable by one of said key controlled printing instrumentality selecting mechanisms to prevent actuation of the dog rocker

without preventing actuation of the associated printing instrumentality when said selecting mechanism is actuated.

4. In a power-operated typewriting machine, the combination of a reciprocable universal actuator, type keys, type carriers, individual actuating means for the type carriers conditionable by the type keys to receive a type carrier impressing blow from the universal actuator, a power mechanism controllable by any one of the individual type carrier actuating means to impart a single limited reciprocation to said actuator through an operating and return stroke of insufficient length to positively move a type carrier to its printing limit, spring means for returning each type carrier and its individual actuating means to normal position following actuation thereof by the actuator, a platen carriage, a platen on the carriage with which the type carriers are coactive to effect printing impressions, an escapement for letter spacing the carriage including a spring returned escapement dog rocker, a spring returned escapement-actuating tappet device for actuating the dog rocker in opposition to the return spring power exerted on the dog rocker, and means positively connected with the universal actuator and having a thrust connection only with said tappet device for moving the latter, in opposition to the return spring power exerted on said device, during type carrier impelling strokes of the universal actuator.

5. A power actuated typewriting machine, as claimed in claim 4, wherein the connection between the escapement actuating tappet device and the dog rocker comprises a hook normally spring held in position for actuation by the escapement-actuating tappet device, and wherein a spring-returned escapement-disabling device is provided having one or more tappet elements for manual actuation of said device by one or more of the type keys and also having a tappet element operable upon said hook to shift the latter out of operative relation to the escapement-actuating tappet device to thereby permit typing operation of selected type carriers of the machine without concomitant letter spacing of the carriage.

6. A typewriting machine, as claimed in claim 2, wherein the impelling spring means for said single mechanism for concomitantly actuating the dog rocker and a selected printing instrumentality comprises constantly tensioned impelling spring means anchored to said mechanism and to the framework of the machine, an auxiliary impelling spring means anchored to said mechanism, and anchoring means on the framework of the machine for said auxiliary spring means manually adjustable to vary the force exerted by the auxiliary spring means on said mechanism, to thereby vary the spring force transmissible by said mechanism to the dog rocker and type carriers of the machine.

7. In a typewriting machine, the combination of a platen carriage, a platen on the carriage, an escapement for the carriage including a spring returned dog rocker, type bars coactive with the platen, a reciprocable universal actuator for the type bars, interponent drivers positively connected with the type bars, return spring means for each type bar and its connected driver, a system of key carrying levers, a system of sub-levers, a system of links connecting the key carrying levers and sub-levers, means carried by each sub-lever for temporarily interposing a different selected one of the drivers in the path of

action of the actuator, power means controlled by each driver to cause a single reciprocation of the actuator when the associated sub-lever is actuated, a separable connection between the dog rocker and actuator for operating the dog rocker in opposition to the return spring force exerted on the latter, and a spring-returned escapement disabling device operable on said separable connection to temporarily break the latter and including portions engageable by selected ones of the sub-levers to actuate said device.

8. In a typewriting machine, the combination of a main frame, a platen carriage mounted on the main frame to travel transversely thereof, a platen on the carriage, a system of type bars located below and in front of the platen and supported in the main frame for upward and rearward swinging of any selected type bar to the platen for printing coaction with the platen, a carriage feeding escapement including a fore-and-aft rockable dog rocker located behind the system of type bars, a fore-and-aft rockable type bar actuating bail located between and below the dog rocker and type bar system and having a horizontal cross-bar extending transversely of the machine and pendent side arms pivoted on the main frame, an operating connection between said actuator and dog rocker, a row of fore-and-aft extending type bar driving interponents positively connected with the type bars and normally aligned horizontally and transversely of the machine out of the field of movement of the cross-bar of the type bar actuator and each having a finger normally extending under said cross-bar and a rearwardly facing shoulder movable upward into the field of movement of said cross-bar, return spring means for each type bar and its connected interponent, a system of sub-levers fulcrumed for rocking about a horizontal axis extending transversely of the machine forward of the system of interponents and each extending downward and then rearward below the system of interponents through said type bar actuating bail, a row of fore-and-aft extending links connected at their rear ends to the downwardly extending portions of the sub-levers, a system of type key carrying levers having upturned key-carrying front end portions and also having upturned rear end portions fulcrumed at their upper ends on the main frame for swinging about a common horizontal axis extending transversely of the machine below the system of type bars, return spring means for each connected key-carrying lever and sub-lever and link, means carried by each sub-lever for shifting a different one of the interponents upwardly to position its rearwardly facing shoulder directly in advance of the cross-bar of the actuating bail to receive a blow from said cross-bar, and power means controlled by lifting movement of any one of said interponents to rock said actuating bail first forward and then rearward and thereafter hold the bail in normal retracted position.

9. A typewriting machine as claimed in claim 8, wherein the key levers are of different length to support the keys in four rows extending across the machine, the sub-levers are all identical, and the links connecting the key-carrying levers and sub-levers are all of the same length and are connected to the downwardly extending portions of the sub-levers at different elevations for the different rows of keys for uniform dip of all keys and uniform rocking of the sub-levers by the keys.

10. A typewriting machine as claimed in claim 8, wherein the key levers are of different length to support the keys in four rows extending across the machine, the sub-levers are all identical, and the links connecting the key-carrying levers and sub-levers are all of the same length and are connected to the downwardly extending portions of the sub-levers at different elevations for the different rows of keys for uniform dip of all keys and uniform rocking of the sub-levers by the keys, the tops of all of the keys are normally disposed in a single downwardly and forwardly inclined plane, and a guard plate is held to the main frame in a plane parallel to that of the key tops and has perforations in which the keys are movable down and up, and a spring-returned space bar connected to said dog rocker is mounted within the forward limit of the main frame forward of the keys, is supported in advance of the guard plate for depression to actuate the dog rocker, and has a top thumb-impact receiving surface inclined in a plane parallel to and intermediate those of the key tops and guard plate.

11. A typewriting machine as claimed in claim 8, wherein the key levers are of different length to support the keys in four rows extending across the machine, the sub-levers are all identical, and the links connecting the key-carrying levers and sub-levers are all of the same length and are connected to the downwardly extending portions of the sub-levers at different elevations for the different rows of keys for uniform dip of all keys and uniform rocking of the sub-levers by the keys, the tops of all of the keys are normally disposed in a single downwardly and forwardly inclined plane, and a guard plate is held to the main frame in a plane parallel to that of the key tops and has perforations in which the keys are movable down and up.

12. In a typewriting machine, the combination of a main frame, a system of normally forwardly extending type bars mounted in the frame for upward and rearward swinging of the type bars to print, a type bar actuator mounted on the frame for fore-and-aft movement and having a straight type bar impelling edge extending horizontally transversely of the machine, a row of identical fore-and-aft extending type bar driving interponents positively connected to the type bars and normally aligned horizontally transversely of the machine, each interponent having a rearwardly facing shoulder presentable in front of said actuator edge by upward movement of the interponent, return spring means for each type bar and its driving interponent, a row of identical sub-levers normally aligned horizontally transversely of the machine and each having an upstanding forward portion and a portion extending rearward below the row of interponents, means supporting the upstanding portions of the sub-levers for rocking about a common straight horizontal axis extending transversely of the machine, means on the main frame for supporting the interponents in their normal returned position, interponent lifting means carried by the rearwardly extending portions of the respective sub-levers for lifting of a different interponent by each said means, key levers supporting four rows of keys and fulcrumed on the main frame for rocking about a common horizontal axis extending transversely of the machine and positively connected with the sub-levers for uniform dip of all the keys and uniform rocking of the sub-levers by key depression.

13. In a typewriting machine, the combination of a normally idle and reciprocably mounted type carrier actuator, individual type key operated means for selecting a type carrier for actuation, power operated means for effecting a single reciprocation of said actuator upon actuation of any one of said type key operated means, a second actuator for actuating the letter spacing means of the machine having a lost-motion connection with said type carrier actuator for actuation of the second actuator by the type carrier actuator, means normally and separably engaged with said second actuator for operation by the latter to actuate the letter spacing means of the machine, a disabling device operable on the last-mentioned means to disconnect it from the second actuator, a plurality of tappets detachably held to the disabling device for engagement by selected ones of the key operated means to cause said disabling device to temporarily disconnect the separably engaged means from the second actuator, and a space bar having a lost-motion operating connection with the second actuator to manually operate the second actuator independently of actuation of the type carrier actuator.

14. In a typewriting machine, the combination of a platen carriage, a platen on the carriage, a letter feed escapement for said carriage including a spring-returned escapement dog rocker, spring-returned individual type bar actuating means, type bars each coactive with the platen and positively connected with a different one of said individual type bar actuating means, a tappet mechanism, spring means for actuating said tappet mechanism to concomitantly impel the dog rocker and any selected one of said individual type bar actuating means in opposition to the return spring force exerted on said dog rocker and the selected type bar actuating means to trip the carriage escapement and effect a type impression, a single cycle power mechanism for automatically restoring the tappet mechanism following each actuation of said tappet mechanism by its actuating spring means and releasably holding said tappet mechanism in restored condition, type keys for the respective type bars, and a plurality of individual spring-returned means each positively connected with a different type key for manual operation thereof upon depression of its connected key to concomitantly release the tappet mechanism and condition the individual actuating means for the associated one of the type bars to receive an impelling blow from the tappet mechanism upon the ensuing spring actuation of the released tappet mechanism.

15. A typewriting machine according to claim 14, wherein the tappet mechanism comprises an escapement tripping tappet and an actuating tappet for the several individual type bar actuating means, wherein a tripping element is pivotally held to the escapement dog rocker for swinging of said element into and out of the field of movement of the escapement tripping tappet and is normally yieldingly held positioned for actuation by said tappet, and wherein means are provided operable by one of said individual type key operated means, upon depression of the associated type key, to swing said tripping element out of the field of action of the escapement tripping tappet.

16. In a typewriting machine, a platen carriage, a platen on the carriage, a carriage escapement including a spring returned escapement dog rocker, an oppositely shiftable and normally idle

type carrier actuator, type carriers normally disconnected from said actuator, spring means for moving said actuator from idle position to impart a printing stroke to any selected one of the type carriers, superior power means for automatically restoring the actuator to idle position, means for automatically releasably locking the actuator in idle position upon restoration of the actuator, type keys for the respective type carriers, means operable by depression of either one of the type keys to concomitantly release the actuator from said locking means and establish a driving connection between the actuator and the type carrier associated with the depressed key, an element positively connected with said actuator for opposite shifting of the element by the actuator, an oppositely shiftable dog rocker tripping tappet, a return spring for said tappet normally yieldingly holding said tappet thrust against said element for movement of the tappet by said element on the spring impelled strokes of the type carrier actuator, a hook pivoted to the dog rocker, a spring connected with said hook to normally hold said hook swung into the field of action of the dog rocker tripping tappet for actuation to rock the dog rocker in opposition to its return spring on the spring impelled strokes of the type carrier actuator, a spring-returned escapement-disabling tappet device, and tappet means operable by one of the type keys upon key depression to actuate escapement disabling tappet device to cause the latter to swing said hook out of the field of action of the dog rocker tripping tappet.

17. In a typewriting machine, a platen carriage, a platen on the carriage, an escapement for the carriage including a spring-returned element movable in opposition to the return spring force imposed thereon for tripping the escapement, a tappet for so moving said element, type carriers, selecting keys for the type carriers, and power actuated means controlled by the respective keys for concomitantly actuating said tappet and a selected type carrier.

18. A typewriting machine, as claimed in claim 17, having a spring-returned manually depressible space bar, and an element positively oppositely shiftable by said bar, and wherein said tappet is movable independently of the power mechanism and said element and is normally yieldingly held in position for thrust actuation of said tappet by said element during the down strokes of the space bar and by said power mechanism during printing strokes of the type carriers.

19. In a key-controlled power-actuated typewriting machine, a main framework including a base casting having side and rear and front walls of a low maximum height not substantially exceeding the maximum height of the keyboard of the machine, four parallel rows of downwardly and forwardly inclined spring-returned manually depressible type keys all lying in a single downwardly and forwardly inclined plane and located within the front portion of said base casting with the front one of said rows of keys close to the front wall of said casting, the front wall of said casting being recessed along both its top and front faces intermediate its ends, a flat forwardly and downwardly inclined guard plate fixed to said base casting and extending rearward beyond the keyboard from the upper edge of the front wall of said casting and having four rows of apertures from which the type keys protrude upward, a manually depressible and spring returned space bar movable down and up in and

substantially covering the recesses in the front wall of said casting and having a flat downwardly and forwardly inclined thumb impact receiving top surface normally disposed in a plane parallel to and intermediate those of the type key tops and said guard plate, means for limiting depressing and return strokes of the type keys, means for limiting depressing and return strokes of the space bar to an extent substantially equal to those of the type keys, the depression limit of the type keys being such that their impact receiving top faces are depressible substantially to the plane of said guard plate, a platen carriage supported on the framework to travel transversely of the machine above the rear portion of the base casting, a platen on the carriage, a system of type bars supported above the base casting intermediate the platen and keyboard, an escapement for the carriage, normally inactive power actuated mechanism for actuating the escapement and type bars located within the rear portion of the base casting, an operating connection between the escapement and power mechanism, individual normally ineffective operating connections between the type bars and power mechanism, means operable by the type keys and located within the base casting for activating the power mechanism for a single cycle of operation and selectively rendering the individual connections between the type bars and power mechanism effective, means located within the base casting and operable by the space bar to manually trip the escapement through a part of the operating connection between the escapement and said power mechanism, and activating power means for said power actuated mechanism located within the framework.

20. In a typewriting machine, the combination of a platen carriage, a platen on the carriage, spring-returned type carriers bearing types co-active with the platen, a letter feed escapement for the carriage including a spring-returned escapement dog carrier, a spring-returned tappet for actuating the dog rocker, a power-actuated tappet mechanism for concomitantly actuating any selected one of the type carriers and said dog rocker actuating tappet in opposition to the return spring forces exerted on said tappet and selected type carrier, spring means for impelling said power-actuated tappet mechanism to so actuate the dog rocker actuating tappet and selected type carrier, power means for retracting said power-actuated tappet mechanism in opposition to said spring means and holding said mechanism retracted, driving interponents positively connected with the respective type carriers and normally out of the field of action of said power-actuated tappet mechanism, spring-returned tappet devices individually operable on the respective driving interponents to position any selected interponent for driving of the latter by the power-actuated tappet mechanism upon spring impulsion of said mechanism, spring-returned means engageable and shiftable by the selected coupler upon positioning movement of the latter by its associated actuating tappet device to release the power-actuated tappet mechanism for impulsion of the latter by said spring means, and a spring-returned tappet means operable on said dog rocker actuating tappet independently of said power-actuated tappet mechanism for effecting letter spacing of the carriage without printing.

21. A typewriting machine, as claimed in claim

20, having a spring-retumed escapement-disabling tappet device operable by either one of a selected plurality of said interponent positioning tappet devices, and a dog rocker actuating interponent connected with the dog rocker and normally yieldingly held positioned for actuation by the dog rocker actuating tappet and movable out of the field of action of the latter by said escapement-disabling tappet.

22. A typewriting machine, as claimed in claim 20, wherein the interponent positioning tappet devices are each individually adjustable

toward and from their associated interponents, the power-actuated tappet mechanism is adjustable toward and from the interponents and the dog rocker actuating tappet, the releasing means for the power-actuated tappet mechanism is adjustable toward and from the interponents, and a dog rocker actuating interponent is held to the dog rocker for actuation by the dog rocker actuating tappet and for adjustment of said interponent toward and from its actuating tappet.

CHARLES WALKER.
